MECHANICAL PENCIL OF THE SCREW
FEED TYPE

John T. Brubaker, Luray, Va.

Application September 21, 1944, Serial No. 555,139

18 Claims. (Cl. 120—18)

1

This invention relates to a mechanical pencil of the screw-feed type.

A prime object is to provide an article of this character having novel means to grip the lead and feed it by rotation of a tubular propeller through which the lead is fed by the gripping means which engages the lead at one or more slots in the tubular propeller.

A second object is to provide a novel expandable and contractile gripper structure operable to release the lead when necessary for re-filling.

Another object is to provide the pencil with a novel slide having gripper means swiveled thereon and engageable with the lead at one or more slots in a rotatable propeller tube, and which gripper means is expandable and contractile in combination with camming means to move the same to lead-releasing position.

Still another object is to provide novel non-rotary means to support the lead without contact with the barrel, engageable and disengageable with the lead under control of an independently adjustable lead-feed tube.

A further object is to provide a novel means to hold the lead in projected position against danger of accidental receding.

The more specific objects and advantages will become apparent from a consideration of the description following, taken in connection with the accompanying drawings illustrating operative embodiments by way of example.

In said drawings:

Fig. 1 is a view through one form of the improved pencil taken approximately centrally and longitudinally;

Fig. 2 is a perspective view showing the novel slidable nut and lead-gripper means swiveled thereon;

Fig. 3 is a cross-section taken on the line 3—3 of Fig. 1;

Fig. 4 is a central longitudinal sectional view taken through a modified form of the pencil;

Fig. 5 is a horizontal section taken on the line 5—5 of Fig. 4;

Fig. 6 is a perspective view of the jaw-separating spring employed in the form of Fig. 4;

Fig. 7 is a substantially central longitudinal sectional view through a further modified form of pencil;

Fig. 8 is a cross-sectional view taken on the line 8—8 of Fig. 7;

Fig. 9 is a fragmentary elevation of the lower portion of the lead propeller used in Fig. 7;

Fig. 10 is a perspective view of that portion of the lead propeller shown in Fig. 9;

2

Fig. 11 is a perspective view of the lead supporting jaws;

Fig. 12 is a view of another modified form of pencil, being partly in elevation and partly in section taken approximately centrally and longitudinally;

Fig. 13 is a cross-section taken on the line 13—13 of Fig. 12;

Fig. 14 is a cross-section taken on the line 10 14—14 of Fig. 12;

Fig. 15 is a fragmentary sectional view of a modified form of lead gripper or feed jaw;

Fig. 16 is a view partly in elevation and partly in approximate longitudinal section through a 15 final modified form of pencil;

Fig. 17 is a longitudinal central sectional view taken at a right-angle to Fig. 16;

Fig. 18 is a cross-section taken on the line 18—18 of Fig. 17; and

Fig. 19 is a cross-section taken on the line 20 19—19 of Fig. 16.

Referring specifically to the drawings wherein the same reference characters designate the same or similar parts through the different views, and 25 first to the form of Figs. 1 to 3, the improved pencil has a barrel or casing at 10, open at the top and at the lower end, preferably having a tapered portion 11 as shown open at the apex so that the lead or marker 12 may project therethrough.

30 Detachably screw-threaded in the top of the barrel at 13 is a tubular bearing in the form of a plug 14. It will be noted that such plug above the screw-threads 13 engages the inner wall of 35 the barrel along a plain surface 15 of any desired extent. This cap is provided with a resilient clip 16, whereby the pencil may be detachably engaged with a pocket of an article of clothing, or other support.

40 A lead propeller or feed tube is generally designated 17, and located centrally and longitudinally of the barrel. This feed tube is preferably made in a single piece, and at the upper end has a journal 18 rotatably mounted in the bore of the plug 14 as a bearing. A knob or any equivalent 45 19 is threaded or otherwise attached at 20 to the journal 18, and it is adapted to be peripherally manually gripped in order to rotate the feed tube 17 in either direction. The feed tube is held against accidental longitudinal displacement relatively to the bearing 14 since it has a shoulder 20 engaging the under surface of the latter in opposition to the knob 19, such shoulder being formed at the larger end of a cone 21.

50 55 The lead 12 is fed or supplied to the tube 17

from the top and it is adapted to be gripped and progressively fed through the tapered portion 11 by the action of the feeding device generally designated 22 and shown detached in Fig. 2. This device comprises a slideable nut 23 having longitudinal slots 24 in its periphery at diametrically opposite points and slidably engaged with ribs 25 extending inwardly from the inner wall of the barrel 10 and serving to guide the nut longitudinally but non-rotatably. This nut or slide 23 has a neck or extension 26, on which a ring 27 is swiveled, and with which it is interengaged at an annular groove 28 in the extension and an annular rib 29 on the ring. This ring constitutes part of a gripper generally designated 30, and which is completed by one or more resilient arms 31. Each arm adjacent its distal end has a lead gripping jaw 32, which optionally may be serrated or roughened as at 33 to increase its degree of engagement with the lead 12.

Said feed tube 17 has a pair of diametrically opposite longitudinal slots 34 therethrough, although one slot and one arm and jaw 31-32 will suffice in most instances, in which the jaws 32 are positioned to slide. The feed tube 17 has external screw-threads at 35 which are engaged by the screw-threads 36 in the bore of the nut or slide 23.

Extensions or fingers 37 rise from the jaws 32 and are engageable with the exterior surface of the cone 21 and forced at the upper extreme of movement of the feeding device 30 to release the lead preparatory to its being replenished.

Located within the tapered portion 11 of the barrel is a pair of holding jaws 38 adapted at their facing surfaces to contact directly the lead 12, as shown in Figs. 1 and 5. The upper or larger ends of jaws 38 are engaged by a disk or plate 39, rigid on or integral with and forming part of the feed tube 17. These jaws 38 may be independent of the feed tube, but as shown they are preferably interconnected therewith as by means of pins 40, rising one from each jaw, occupying diametrically arranged slots 41 in the disk 39 and being held against detachment therefrom by heads 42 on the pins 40.

The construction described is such that all parts as a unit are slidably removable from and replaceable into the barrel 10 through the detachment of plug or tube 14 at the screw-threads 13, it being clear that the jaws 38 will be withdrawn with the feed tube 17 in view of the interconnection therewith at the pins 40, and notwithstanding the presence of the ribs 25, since the slots 41 may be registered therewith and slidably receive the same.

In the use of the pencil, it is to be observed that the jaws 38 project below the portion 11 of the barrel so that the lead will be supported by the jaws and cannot contact the barrel which is a cause of frequent fracture of lead in existing constructions. Also the degree of pressure which the jaws 38 have on the lead may be regulated by the longitudinal position of the feed tube 17 governed by the adjustment or position of the plug 14, which correspondingly presses the disk 39 against the upper ends of the jaws or recedes therefrom to enable the jaws to separate by upward movement along the inclined surfaces of the tapered portion 11. It will be clear that the parts are so proportioned as to accommodate lead of various diameters or thicknesses, it being realized that the differences in the diameters usually is in thousandths of an inch.

Further, with respect to operation, the lead 12

may be in any desired lengths and it is propelled or fed through the bore or central opening of the feed tube 17 by successive rotations of the knob 19 according to the extent which the lower end of the lead abrades or wears. Through such rotation of the knob 19 in one direction, tube 17 will be turned so that its screw-threads 35 through interengagement with those at 36 will move the slide 23 as suggested in the dotted line position of Fig. 1, during which action, the lead will be gripped by the jaws 32 since the resilient arms 31 are biased to contract or move toward each other. However, when the lead is worn, and needs replenishing, knob 19 is turned in the retrograde direction to move the feeding device 22 upwardly to the full line position of Fig. 1, during which movement the fingers contact the cam or cone 21 and separate the jaws 22 and thus release the used or short length of lead. Such separation of the jaws need merely be a matter of a thousandth or a few thousandths of an inch. When the jaws are thus separated, a new length of lead 12 is supplied to the pencil and the knob 19 slightly turned in the opposite direction so that the jaws under their bias will grip the lead which may thereafter be fed through the operation of the pencil as described.

Referring now to Figs. 4 to 6, wherein a modified form of lead holding jaws is shown, the lead is held in writing position and against recession therefrom by a plurality of jaws functioning generally like those at 38 and designated 47. Jaws 47 extend below the barrel as in the first form of the invention for the same purpose, and the surfaces thereof which contact and hold the lead 46 are serrated or otherwise roughened as at 48. The upper outer edges of the jaws 47 are preferably cut away at 49 to provide clearance for upward adjustment or variation of the position of jaws 47.

When the feed tube recedes, the jaws 47 will separate and move upwardly by reason of their contact with the tapered wall of the lower portion 50 of the barrel and also by reason of the expansive or straightening action of an arcuate spring 54 which is located in a recess 55 of one of the jaws 47, and which spring in its terminals has notches 56 of sufficient size to enable the lead 46 to be fed without contact with such spring 54. It is to be understood that in all positions of the jaws 47 the serrations 48 will hold the lead against recession or retraction; and it is to be understood that these serrations and/or spring 54 may be used in the first form as well as all succeeding forms of the invention.

Another modified form of the invention is disclosed in Figs. 7 to 11. In this form I use a barrel or casing 10' having a lower tapered end portion 11'. At the upper end, a tubular bearing 14' is screw-threaded as at 13' having a resilient attaching clip 16' thereon. A pair of diametrically opposite longitudinal ribs 25' are provided on the interior of the wall of the barrel 10'. Operable centrally and disposed longitudinally within barrel 10' is a feeding tube structure generally designated 57, preferably in a single piece. This structure includes a tubular journal 18' and the structure 57 has a central longitudinal bore 58, through which the lead 12' is supplied from above. An operating knob 19' is secured to the upper end of the journal 18' as at 20' in any suitable manner in opposition to a shoulder 20' formed at the upper end of a conical cam 21'.

75 All parts described with primed numerals cor-

respond in construction and operation to the same numerals unprimed as used in the first form.

The feed tube structure 57 throughout most of its length has a helical slot 58, into which project one or more gripping-jaws 59, preferably roughened or serrated at their inner ends at 60 for direct engagement with the lead 12'. Jaws 59 are carried by arms 31' mounted in any suitable manner on a slide 61, which have peripheral slots 62 interengaged with the ribs 25' so that the slide cannot turn. The slide also has a bore or central opening 63 so that it may freely slide along the tube structure 57. Jaws 59 have spreading fingers 37' to co-act with the cam or cone 29' for the same reaction as is true between the fingers 37 and cam 31 in the first form.

The knob 19' may be turned in either direction to turn the feeding device 57 accordingly and through such turning, the interengagement of the jaws or grippers 59 with the helical groove 58 will move the slide 61 longitudinally of the barrel, the jaws 59 functioning like the jaws 32 of the first form, and in addition functioning as a propelling means in view of the interengagement of the grippers 59 with the helical groove or slot 58. Movement of the arms 31' to the upper limit in Fig. 7 causes fingers 37' to their contact with the cone 21' to spread and release the lead. In the dotted line position of Fig. 7, the lead will be gripped by the jaws 59 so as to be fed through rotation of the feed tube 57 and sliding of element 61.

Tube 57 and parts connected thereto may be removed and replaced as a unit like the generally corresponding parts in the other forms of the invention. The tube structure 57 in this form, however, has a plate or disk 64, at its lower end in contact with the upper surfaces of gripping jaws 65 for the lead 12', the disk having slots 66 in its periphery for registry with the ribs 25' to enable removal thereover. The jaws 65 are loose within the tapered portion 11' and function generally like those at 33 and 41, being loose and gripping the lead 12' at their facing surfaces. Disk 64 has a bifurcated downward extension forming generally triangular tines 67 which are of less thickness than the lead 12' and which are disposed between the jaws 65. The rotation of the feed tube 57 since the tines 67 are rigid therewith, will also rotate the jaws 65. The adjustment of feed tube 57 at the threads 13' determine the degree of gripping of jaws 65 against the lead, it being clear that opposite movement of the feed tube 57 will permit expansion of the jaws 65 to accommodate thicker leads or leads of greater diameter.

A further modified form is shown in Figs. 12 to 14. This form of the invention primarily differs from the first form in that a feeding device 22' generally similar to that employed at 22 is operable in a position inverted with respect thereto, and with arms and jaws biased to expand rather than to contract. The barrel 10'a conforms to that employed at 10, and the bearing or head 14'a conforms to that at 14, being, if desired, the same as the latter and in screw-threaded attachment and adjustment at 13'a with said barrel 10'a. The attaching clip is designated 16'a and the barrel has ribs 25'a like those at 25. The lead feed tube 17'a is generally like that employed at 17, being rotatable at a journal 18'a within the head 14'a and rotatable in either direction through the manipulation of a knob 19'a screw-threaded or otherwise secured thereto. Said knob 19'a and a pin or shoulder 21'a attach tube 17'a to bearing 14'a.

Said feed tube structure 17'a has a disk at 39'a and all parts carried by the tube are detachable and replaceable as a unit as in the other forms, the disk 39'a having slots 68 for registration with and sliding over the ribs 25'a. Depending from the disk 39'a is a split holder tube 69, the same having one or more longitudinal slits as shown. The lead feed tube 17'a has a central longitudinal bore or opening, through which the lead 70 is supplied from the top. The slit or slits at 71 in tube 69, enable the tube to be contracted about different sizes of lead 70, according to the adjustment of jaws 72, and between which a holder tube 69 extends, and which jaws are engaged at their upper or larger ends by the disk 39'a and are housed within a lower conical portion 11'a of the barrel 10'a, the holder tube 69 extending below the barrel so as to support the lead without contact with the latter. The position of the jaws 72 is governed by the adjustment of the plug 14'a at the screw-threads 13'a. Although I have shown a different means for holding engagement with the lead at the lower end of the pencil, in this form, it is to be understood that I may interchangeably use such lead holding means at the lower end as is shown in any of the other forms of the invention. This is true not only in this modified form, but in all other forms.

Reverting to the lead feed device 22', the same has a nut 23'a in screw-threaded engagement with the exterior screw-threads of the feed tube 17'a at 35'a, such nut being slidable but non-rotatable in view of the interengagement of slots 24'a with the ribs 25'a. Swiveled on an extension 26'a of nut 23'a in the same manner as between the nut 23 and ring 27 in the first form is a ring 27'a, from which depend resilient arms 31'a biased to expand or separate at lead-gripping members or jaws 32'a, which extend through diametrically opposite slots 34'a in the feed tube 17'a to mount slidably but non-rotatably the feed device 22'. When this device 22' is practically in its uppermost position, the jaws 32'a expand into an annular groove 73 provided in the inner surface of the barrel 10'a. It will be noted that the outer portions of the jaws as at 74 present rounded noses, so that the jaws extend into the groove to release short lengths of lead. The device 21' is moved in either direction according to the direction of turning of knob 19'a and when the noses 74 move out of the groove 73 they are moved or compressed toward each other by the wall defining groove 73 which thus functions as a cam. The jaws will thus feed or move the lead longitudinally of the feeder device 17 according to the operation of the latter. In Fig. 12, the jaws are shown in full lines in the lead-releasing or expanded position, while in dotted lines such device 22' is shown in the lead-gripping and feeding condition.

Referring now to the final modified form of Figs. 16 to 19, it embodies the same general principles as the preceding forms, but the feeding movement of the parts is greatly shortened. In this form, the barrel is shown at 10'b and at its lower end has a conical or tapered portion 11'b while at the upper end it is closed by a bearing member 14'b screw-threaded as at 13'b into the casing or barrel 10'b. A resilient attaching clip 16 extends from the bearing 14'b.

Journalized in the bearing 14'b is a lead feed tube 17'b having a central longitudinal bore 17'c through which the lead 12'b is supplied from above and fed.

Retained in the conical portion 11'b are lead gripping jaws or segments 38'b, adapted at their flat surfaces to engage said lead 12'b. Said jaws

at their flat surfaces may be plain, but are preferably serrated or roughened as at 38^c in order to hold the lead 12^b against retraction or recession into the barrel, but capable of extension slidably through and beyond the jaws 38^b as required as the lead wears. It will be noted that such jaws extend outwardly beyond the barrel so as to support the lead directly without contact thereof against the barrel. Such serrations or teeth at 38^c preferably provide horizontal shoulders 38^d and upwardly and outwardly inclined surfaces 38^e connecting them.

Tube 17^b is held in the bearing 14^b against longitudinal movement by means of a pin or shoulder 21^b engaging the inner end of the latter, and by means of a knob 20^b engaging the outer end of the latter, such knob being screw-threaded to tube 17^b as in the preceding forms or attached in any other desired manner. At the inner end, tube 17^b has a disk or head 39^b engaged with the upper ends of the jaws 38^b so as to give the requisite pressure against the latter to clamp the lead 12^b, according to its size, it being clear that through turning of the bearing 14^b that the feed tube 17^b will be longitudinally adjusted according to the position desired for said jaws 38^b dependent on the size of the lead 12^b. Disk 39^b is provided with radial peripheral slots 41^b to enable the feed tube and all parts carried thereby to be removed and replaced as a unit, such slots 41^b enabling passage over relatively short diagrammatically opposite ribs 25^b carried on the inner wall of barrel 10^b.

Said feed tube 17^b to a limited extent has screw-threads 35^b provided thereon, and on which a nut 23^b is screw-threaded at its bore. This nut has slots 24^b corresponding to those at 41^b, inter-engaged with the ribs 25^b so that the nut cannot turn although it will slide through rotation of feed tube 17^b. A ring 27^b is swiveled on an extension or neck 26^b in the same manner that the ring 27 is swiveled on the nut 23. This ring 27^b has one or more resilient jaws or grippers 31^b depending therefrom and extending through the slots 34^b provided diametrically in the feed tube 17^b. Such jaws optionally serrated at 38^b and are biased or function to grip the lead 12^b in order that the lead may be positively fed through the rotation of the knob 20^b which will turn the feed tube 17^b and cause sliding of the nut 23^b, ring 27^b and the jaws or grippers. It will also be noted that the lower end walls at the slots 34^b are inclined at 37^b so that adjacent the lower extremity of movement of the jaws, they will be automatically separated through the turning of the knob 20^b and feed tube to release the lead, although the lead cannot recede due to its engagement by the teeth 38^c. With the jaws either separated or at their uppermost limit of movement, a new lead may be pushed down the feed tube until it is frictionally gripped by the teeth 38^c above the short length of lead remaining between jaws 38^b, and thereafter jaws 33^b may be fed downwardly to correspondingly feed the new lead against said short length of lead through the turning of the knob 20^b.

It will be noted that in this final form of the invention, successive relatively short feed movements for the lead are provided. Such a construction considerably reduces manufacturing costs.

In all forms of the invention, in lieu of the various jaws or grippers described, such as those at 31, I may use the modified form disclosed in Fig. 15. In this modified form, each arm is resilient

such as that at 31^e which corresponds to that at 31. For instance, this arm may be biased to contract or expand according to the form of the invention in which it is used, and it has a surface 5 at 33^e to engage the side of a lead such as 12, which surface may optionally be plain or serrated. This arm 31^e has a lug or flange 75 which will overlap the upper end of the lead in order to provide a shoulder to push against it in addition to the frictional gripping of the side of the lead by the wall 33^e.

Attention is called to the fact that in all forms of the invention, the various parts are adapted for interchanging or each form is adapted to be modified or re-built embodying the parts and principles of the others. In addition, the parts may be made of any suitable materials, particularly metal, plastics or the like or be composite.

I claim as my invention:

20 1. A pencil having a barrel, a rotatable lead feed tube disposed within and longitudinally of the barrel, said tube having its bore opening at the top for supply of lead from the exterior of the pencil, a slide within the barrel, coacting means on the slide and the tube to move the slide along the tube through rotation of the latter, means to hold the slide from rotation relatively to the barrel, said tube having a slot, and the last-mentioned means being positioned through the slot for feeding engagement with lead in the barrel.

25 2. A pencil having a barrel, a rotatable lead feed tube disposed within and longitudinally of the barrel, said tube having its bore opening at the top for supply of lead from the exterior of the pencil, a slide within the barrel, coacting means on the slide and the tube to move the slide along the tube through rotation of the latter, means to hold the slide from rotation relatively to the barrel, said tube having a slot, the last-mentioned means being positioned through the slot for feeding engagement with lead in the barrel, and means against which the last-mentioned means is operable to impart a lead-releasing 40 movement to the latter.

30 3. A pencil having a barrel, a rotatable lead feed tube disposed within and longitudinally of the barrel, a slide within the barrel, coacting means on the slide and the tube to move the slide along the tube through rotation of the latter, means to hold the slide from rotation relatively to the barrel, said tube having its bore opening at the top for supply of lead from the exterior of the pencil, said tube having a slot, the last-mentioned means being positioned through the slot for feeding engagement with lead in the barrel, a cam surface on one of the parts, and the last-mentioned means being movable against the cam means to impart a lead-releasing 45 movement thereto.

35 4. A pencil having a barrel, a rotatable lead feed tube disposed within and longitudinally of the barrel, a slide within the barrel, coacting means on the slide and the tube to move the slide along the tube through rotation of the latter, means to hold the slide from rotation relatively to the barrel, said tube having a slot, the last-mentioned means being positioned through the slot for feeding engagement with lead in the barrel, a bearing in the barrel journaling and carrying said tube, jaw means to grip the lead at the outlet end of the barrel, and means adjustably maintaining the bearing in the tube to control the movement and pressure of the jaw means 50 with respect to the lead.

5. A pencil having a barrel, a rotatable lead feed tube disposed within and longitudinally of the barrel, a slide within said barrel having a lead gripping jaw thereon, means to hold the slide from rotation relatively to the barrel, said feed tube having a helical slot, said jaw extending into the slot and being positioned to function dually to grip and feed lead passing therethrough and to follow the helical slot.

6. A pencil having a barrel, a rotatable lead feed tube disposed within and longitudinally of the barrel, a slide within said barrel having a lead gripping jaw thereon, means to hold the slide from rotation relatively to the barrel, said feed tube having a helical slot, said jaw extending into the slot and being positioned to function dually to grip and feed lead passing therethrough and to follow the helical slot, a cam on said feed tube, and said jaw being movable against said cam for lead releasing movement.

7. A pencil having a barrel member, a rotatable lead feed tube member disposed within and longitudinally thereof, a slide within the barrel member, coacting means between the slide and the tube member to move the slide along the tube member through the rotation of the latter, means to hold the slide from rotation relatively to the barrel, said tube member being slotted, means on the slide to grip and release lead for feeding movements, a cam on said feed tube, and said second-mentioned means being biased to move to lead-releasing position when engaging said cam.

8. A pencil having a barrel member, a lead feed tube disposed within and longitudinally thereof, a slide within the barrel means to hold the slide against rotation with respect thereto, a jaw on said slide, said tube having a helical slot therethrough, and said jaw extending through said slot functioning dually to grip and feed lead and to follow said slot to impart feeding movement to the lead.

9. A pencil having a barrel member, a rotatable lead feed tube member disposed within and longitudinally thereof, a slide within the barrel member means to hold the slide against rotation relatively the barrel member, a swivel attached to said slide, inter-engaging screw-threads on the tube member and slide said tube member having a slot, and a jaw member on the swivel extending into the slot and engageable with lead therein to feed the same.

10. A pencil having a barrel member, a rotatable lead feed tube member disposed within and longitudinally thereof, a slide within the barrel member means to hold the slide against rotation relatively the barrel member, a swivel attached to said slide, inter-engaging screw-threads on the tube member and slide said tube member having a slot, a jaw member on the swivel extending into the slot and engageable with lead therein to feed the same, jaw means at the writing end of the barrel having camming engagement with the latter for movement into contact with lead, and means to adjust the position of the tube member relatively to the jaw means to control the position of the latter and its degree of gripping engagement with lead.

11. A pencil having a barrel member, a rotatable lead feed tube member disposed within and longitudinally thereof, a slide within the barrel member means to hold the slide against rotation relatively thereto, a swivel attached to said slide, inter-engaging screw-threads on the tube member and slide, said tube member having a slot, a

jaw member on the swivel extending into the slot and engageable with lead therein to feed the same, jaw means at the writing end of the barrel having camming engagement with the latter for movement into contact with lead, means to adjust the position of the tube member relatively to the jaw means to control the position of the latter and its degree of gripping engagement with lead, and means interconnecting the tube member and jaw means for movement of the latter unitarily with the tube member and for spreading movement.

12. A pencil having a barrel member, a rotatable lead feed tube member disposed within and longitudinally thereof, a slide within the barrel member means to hold the slide against rotation relatively the barrel member, a swivel attached to said slide, inter-engaging screw-threads on the tube member and slide said tube member having a slot, a jaw member on the swivel extending into the slot and engageable with lead therein to feed the same, said jaw member being resilient, a cam on the tube member, and means on the jaw member engageable with the cam adjacent one extremity of movement of the swivel to move the jaw member to lead releasing position.

13. A pencil having a barrel, a rotatable lead feed tube disposed within and longitudinally thereof, a bearing screw-threaded in the upper end of the barrel for adjustment, said tube being journalled in said bearing, and extending exteriorly thereof so that it may be gripped for manual operation, said barrel having an internal longitudinally extending spline, a nut in screw-threaded engagement with the tube having a slot interengaged with the spline, a ring having a flange attaching and swiveling it on the nut, a pair of opposed lead gripping jaws extending from the ring, said tube having oppositely aligned slots, said jaws extending into said slots for gripping engagement with lead therein.

14. A pencil having a barrel, a rotatable lead feed tube disposed within and longitudinally thereof, a bearing screw-threaded in the upper end of the barrel for adjustment, said tube being journalled in said bearing, and extending exteriorly thereof so that it may be gripped for manual operation, said barrel having an internal longitudinally extending spline, a nut in screw-threaded engagement with the tube having a slot interengaged with the spline, a ring having a flange attaching and swiveling it on the nut, a pair of opposed lead gripping jaws extending from the ring, said tube having oppositely aligned slots, said jaws extending into said slots for gripping engagement with lead therein.

15. A pencil having a barrel, a bearing adjustably screw-threaded in the upper end thereof, a lead feed tube rotatably mounted in said bearing and disposed within and longitudinally of the barrel, an operating element on the tube engaging the outer end of the bearing, said tube having a cam provided with a shoulder engaging the inner end of the bearing, said tube having a helical slot therethrough, a slide surrounding the tube, means to hold said slide against rotation relatively to the

along upwardly inclined surfaces, said disk having inwardly extending slots, the last-mentioned jaws having studs retained by the disk and slidably movable in said slots, one of said slots also functioning to clear said spline to enable removal of all parts with the tube as a unit.

barrel, jaws extending from the slide having portions entering said slot functioning dually to follow the same to cause the nut to slide and to grip the lead between them, said jaws being resilient and adapted to contact said cam adjacent one extremity of movement to separate the jaws to release the lead.

16. A pencil having a barrel, a bearing adjustably screw-threaded in the upper end thereof, a lead feed tube rotatably mounted in said bearing and disposed within and longitudinally of the barrel, an operating element on the tube engaging the outer end of the bearing, said tube having a cam provided with a shoulder engaging the inner end of the bearing, said tube having a helical slot therethrough, a slide surrounding the tube, means to hold said slide against rotation relatively to the barrel, jaws extending from the slide having portions entering said slot functioning dually to follow the same to cause the nut to slide and to grip the lead between them, said jaws being resilient and adapted to contact said cam adjacent one extremity of movement to separate the jaws to release the lead, a disk at the lower end of the tube, jaws to grip the lead at the lower end of the tube disposed within the latter and engaging the same along inclined surfaces, said jaws being engageable at their upper ends by said disk, and said tube having a bifurcated downward extension disposed between the jaws and of less thickness than the lead to be engaged by the latter.

17. A pencil having a barrel, a lead feed tube rotatable therein and disposed longitudinally thereof, a nut threaded on said tube, means holding said nut against rotation relatively to the barrel, a swivel attached to said nut having a jaw, said tube having a longitudinally extending slot through which a portion of the jaw projects for feeding contact with lead therein, the inner wall

of the barrel having a concavity, and said jaw being resilient and normally tending to move into said concavity in lead-releasing position.

18. A pencil having a barrel, a lead feed tube rotatable therein and disposed longitudinally thereof, a nut threaded on said tube, means holding said nut against rotation relatively to the barrel, a swivel attached to said nut having a jaw, said tube having a longitudinally extending slot through which a portion of the jaw projects for feeding contact with lead therein, the inner wall of the barrel having a concavity, and said jaw being resilient and normally tending to move into said cavity in lead-releasing position, said tube having an extension at the writing end of the pencil through which the lead extends, said extension being split, and means engaging the extension and barrel under control of the tube to regulate the contraction of the extension with respect to the lead therein.

JOHN T. BRUBAKER.
